UNITED STATES PATENT OFFICE.

THEODORE E. LUTZ, OF GALION, OHIO.

CLOSURE FOR BURIAL-VAULTS.

1,303,087.

Specification of Letters Patent.

Patented May 6, 1919.

Application filed April 27, 1917. Serial No. 164,981.

To all whom it may concern:

Be it known that I, THEODORE E. LUTZ, a citizen of the United States, residing at Galion, in the county of Crawford and State 5 of Ohio, have invented a new and useful Closure for Burial-Vaults, of which the following is a specification.

This invention has reference to closures for burial vaults intended for sealing and 10 locking grave vaults and the like, although the invention is also adapted for closing various other openings than those leading into a burial vault.

The object of the invention is to provide 15 a closure or door which may be hermetically sealed by the act of closing the door, and which may or may not be locked in the closed position against the possibility of opening, except by the use of force destruc- 20 tive to the door or vault, the invention comprising certain constructions and combina- tions hereinafter set forth.

The invention will be best understood 25 from a consideration of the following de- tailed description, taken in connection with the accompanying drawings forming part of this specification, with the further under- standing that while the drawings show a practical form of the invention, the latter is 30 not confined to any strict conformity with the showing of the drawings, but may be changed and modified so long as such changes and modifications come within the scope of the appended claims.

35 In the drawings:—

Figure 1 is an elevation of the rear face of the door or closure, showing the vault in cross-section and the bolts projected.

Fig. 2 is a view similar to Fig. 1 with the 40 bolts retracted, the showing of Fig. 2 being less extensive than that of Fig. 1 and drawn on a larger scale.

Fig. 3 is a section on the line 3—3 of Fig. 1 with some parts in elevation, but drawn on 45 a larger scale, and showing the parts before movement into the door clamping position.

Fig. 4 is a view similar to that of Fig. 3 with some parts in elevation and showing the locking members of the door in the door 50 clamping position.

Fig. 5 is a face view of a master plate used

in the door locking mechanism, the view being of that side of the plate toward the door.

Fig. 6 is a section on the line 6—6 of 55 Fig. 5.

Fig. 7 is a face view of the female member of the lock manipulating means.

Fig. 8 is a section on the line 8—8 of 60 Fig. 7.

Referring to the drawings there is shown a grave vault 1 which may be constructed of sheet metal, and which may be taken as indicative of any suitable form of grave vault or other inclosure, since the invention is not of necessity limited to doors or closures for grave vaults. Secured to the walls of the vault about the entrance end thereof is an angle abutment strip 2 with one flange made fast to the vault by rivets 3 or otherwise, 65 so that the other flange 4 of the strip is perpendicular to the walls of the vault and constitutes an inset abutment, the strip 2 being located a short distance into the vault.

There is also provided a door or closure 5 75 in the form of a plate of sheet metal of such size as to fit easily into the mouth of the vault and engage all about the edges against the web 4 of the strip 2, it being customary to interpose a gasket 6 between the door of 80 the vault and the abutment strip 2. Such gasket may be made of rubber or any other desirable material.

For reasons which will hereinafter appear, the door 5 is made of material of suffi- 85 ciently light gage that when the door is clamped in place it will bulge outwardly at the central portions and the material is sufficiently elastic to tend to return to its initial flat condition when relieved of the bulging 90 pressure.

The top of the vault is usually more or less crowned, and intermediate of the width of the vault the top portion carries a hinged member 7 in which engages a companion 95 hinge member 8 riveted or otherwise secured to the door on the outer face thereof close to what constitutes the top edge of the door. The hinge member 7 in the particular showing of the drawings rises above the top of 100 the vault, and the hinge member 8, which has eccentrically disposed pintles 9 thereon,

is lodged in elongated sockets 10 in the hinge member 7. By this construction the door may be opened for entrance into the vault, and when closed may move bodily into the mouth of the vault for a sufficient distance to compress the packing 6.

At the central portion of the door there is provided a passage 11 through which extends an elongated nut 12 having both interior and exterior screw threads, and also provided at one end with an outstanding flange 13 to abut against the inner face of the door. The nut 12, which constitutes the female member of the lock manipulating structure, has a lock nut 14 applied to its exteriorly threaded portion at the part thereof which projects through the passage 11 to the outside of the door plate. The nut 14 provides means whereby the female locking member may be tightly clamped to the door, or may be loosened therefrom for a purpose which will presently appear. A packing washer 15, preferably of lead, is interposed between the nut 14 and the outer face of the door and is of a size to effectively close the opening 11 when the nut 14 is screwed tight. The female member 12 is continued beyond the flange 13 for a short distance, and there is provided on its end face with a series of radial notches 16. The flange 13 has a radial projection 17 beyond the peripheral margin of the flange, and this projection 17 carries a stud or pin 18 parallel with the longitudinal axis of the member 12. Furthermore, the flange 13 is formed with peripheral notches 19, in either one of which a dog 20 may engage, such dog being on one end of a spring arm 21 mounted on a stud 22 projecting from the inner face of the door 5 and put under appropriate spring tension by a stop pin 23 also projecting from the inner face of the door 5 in the path of the arm 21. The dog 20 serves to locate and temporarily hold the female member 12 in different positions about its longitudinal axis.

That end of the female member 12 remote from the flange 13 is provided with diametrically opposite recesses 24 which are always exposed on the exterior of the door and are designed to receive a tool for turning the member 12.

Threaded through the member 12 is an exteriorly threaded screw rod 25 constituting the male member of the lock manipulating structure. At what constitutes the outer end of the rod 25 is a squared portion 26 for the application of a turning tool, although it will be understood that the manipulating end of the rod 25 may be otherwise formed than as shown and described. The rod 25 is of sufficient length to enter the vault beyond the inner face of the door for a considerable distance, and terminates in a rounded axially extended portion 27 which passes

through a corresponding opening 28 in a plate 29 serving as a master plate. In order to hold the master plate and rod 25 together without interfering with the turning of the rod 25 with respect to the master plate, the rounded portion 27 is traversed by a cotter pin 30 as a simple means for the purpose. The master plate 29 is formed about the opening 28 with a series of lugs 31 conforming in spacing and shape to the notches 16, and in the particular showing of the drawings both the notches 16 and lugs 31 are shown as of V or triangular shape, although such particular shape is not obligatory.

The master plate is provided with a circular series of radially extended ears 32, each having a hole or passage 33 therethrough, and one or more of these ears has, or may have, a lip 34 projecting therefrom for a purpose which will hereinafter appear.

Projecting through each passage 33 of the master plate is an angle nose 35 on one end of a link 40 having the other end 41 bifurcated and straddling the apex end of a triangular skeleton lock bolt 42 having a basic spread to include the greater portion of the top, bottom or sides of the vault in accordance with the portion of the vault toward which the lock bolt is directed. The bifurcated end 41 is joined to the corresponding portion of the lock bolt by a pivot 41^a which may be in the form of a rivet, and which together with the bifurcated end 41 makes the link 40 substantially a part of the lock bolt, although hinged thereto and capable of transmitting to the lock bolt certain forces to which it is subjected. Each lock bolt 42 has at its basic end a series of locking fingers 43 for projection into engagement with that face of the web 6 of the angle strip 2 remote from the closure plate 5 when the latter is in closing relation to the mouth of the vault. Each finger 43 projects through a stud 44 having a slot 45 formed in it for the purpose. The slot 45 has a rounded wall 46 on which the finger 43 may rock. The stud 44 is fixed to the plate 5 by an upset rivet extension 47, or in any other suitable way. Each stud 44 is located close to the outer edge of the plate 5, but sufficiently spaced therefrom so that the studs, which are on the inner face of the plate 5, may project into the vault. The arrangement is such that the rounded walls 46 of the studs constitute fulcrum points for the lock bolts, so that when the bolts are rocked about the fulcrum points 46 away from the inner face of the plate 5, the outer ends of the fingers 43 bearing against the inner face of the web 4 will force the marginal portion of the plate 5 into tight relation to the angle strip 2 with the gasket 6 intervening, wherefore there is produced a hermetically sealed joint.

Studs 48 are provided on the webs of the

skeleton lock bolts close to the lugs 44 to limit the movement of the lock bolts toward the plate 5 and prevent looseness of parts in such position.

5 To guide the lock bolts and constrain their movements on lines perpendicular to their long sides, other studs 49 are secured to and project from the inner face of the plate 5 in position to extend through elongated slots 50^a in the apex portions of the lock bolts 42. These studs are long enough to permit the rocking movements of the lock bolts about the walls 46 of the studs 44.

Pivoted to one of the lock bolts 42 near its 15 apex end is a plate 50 provided near one end with a longitudinal slot 51 having offset portions 52 constituting notches. At the other end the plate 50 is provided with a recess 53 shaped to partially embrace a stud 49. A 20 spring 54 has one end made fast to the lock bolt 42 at a convenient point and the other end 55 movable in the slot 51 and formed to engage in either of the notches 52, the arrangement being such that when the spring 25 54 has its end 55 in one of the notches 52, the recessed end 53 of the plate 50 is drawn and held to one side of the corresponding stud 49, and when the end 55 of the spring 54 is in the other notch 52, the plate 50 has 30 imparted to it a tendency to rock so as to bring the recess 53 into such relation to the stud 49 as to engage the latter when the lock bolt is projected into the locking position. The plate 50, which is intended to serve as a 35 permanent holding device for the lock bolts when in their projected position, may be adjusted to either remain inactive or to automatically secure the door in the permanently locked position against removal except by 40 the employment of forces destructive to material parts of the structure.

While a single locking device 50 has been shown as applied to one only of the lock bolts 42, it will be understood that more of 45 these lock bolts may be used if desired.

To facilitate the manipulation of the door, a handle or handles 56 are made fast to the outer face thereof at a convenient point.

When the locking mechanism for the door 50 has the bolts 44 retracted, said bolts are then in substantially parallel relation with the plate 5 and close to it. This means that the screw rod 25 is in its position of greatest projection from the front face of the door, 55 as shown in Fig. 3, thus bringing the lugs 31 into seating relation to the notches 16 of the female member 12, which latter may be turned about its longitudinal axis by a tool applied to the recesses 24, the nut 14 being at the time loosened sufficiently for the purpose. At the same time the lug or pin 60 18 engages the master plate 29 between two adjacent projections 32. The turning of the female member 12 in a clockwise direction as

viewed in Fig. 1, or counterclockwise direction as viewed from the front of the door, results in the withdrawal of the lock bolts to the position shown in Fig. 2 with the dog 20 lodging in an appropriate one of the notches 19, thereby holding the parts temporarily in 70 the assumed position.

Now with the door closed, the female member 12 may be rotated in the opposite direction, that is, in a clockwise direction as viewed from the front of the door, or counterclockwise as viewed in Fig. 2, thus through the links 40 projecting the finger ends 43 of the lock bolts 42 over the rear faces of the flanges 4, and locking the door closed, the dog 20 yielding to such movement and ultimately engaging in the other notch 19 to hold the parts in the new position against accidental displacement. This is a simple unlocking or locking of the door, so that access to the vault may be obtained at any 85 time, but the vault is not sealed hermetically. To produce the hermetic sealing after the door is locked, the nut 14 is tightened, compressing the washer 15 against the outer face of the door, thus accomplishing the 90 sealing at the opening 11. Now, by the application of a suitable tool to the end 26 of the screw rod 25, the latter is moved into the vault through the female member or nut 12, thereby forcing the master plate 29 inwardly away from the inner face of the door and rocking the lock bolts 42 upon the fulcrum supports provided for in the studs 44. During the initial part of this movement the master plate is held from turning movements because of the engagement of the lugs 31 in the recesses 16 and the engagement of the pin or stud 18 between two projections 32 of the master plate, and consequently the links 40 have no pulling action upon the 105 lock bolts 42 tending to retract them. The longitudinal movement of the screw rod 25 may be continued until the packing gasket 6 is tightly compressed, thus hermetically sealing the marginal portions of the door. 110 Should it be desirable to subsequently open the door, the described operations are reversed, the lock bolts are again brought into substantially parallel relation to the door plate 5, and on loosening the nut 14 the female member 12 may be turned to retract the lock bolts.

It is assumed that during these operations the plate 50 is constrained to the inactive position by the proper placing of the 120 spring 54. If it be desired that the locking of the door in the hermetically sealed condition shall be permanent, the spring 54 is adjusted with relation to the plate 50 to constrain the recessed end 53 toward the 125 adjacent guide pin 49. Then when the lock bolts are projected the recessed end 53 will snap into suitably embracing relation to the

pin 49 to prevent subsequent retracting of the lock bolts. One such plate 50 will answer the purpose, but to make the structure more resistant to any attempt to open the door after being permanently locked closed, an additional number of plates 50 may be provided.

The links 40 have strengthening ribs 57, and the lip 34 on the master plate is so placed as to engage the ribbed portion of different links to limit the rotative movement of the master plate in either direction. While the master plate is shown as having but one lip 34 it will be understood that a greater number of lips may be provided.

It will be further understood that wherever additional strength is desired, the parts are provided with strengthening ribs.

20 By making the door plate 5 of more or less spring material pressure is applied effectively to both sides of the packing gasket 6, since the door plate springs outwardly or bulges to some extent, and hence pressure is applied to the gasket over a considerable area, since the marginal portions of the door are held approximately parallel with the outer wall of the flange 4 due to the bulge of the door plate 5, the engagement of the fingers 43 with the inner face of the flange 4 and the action of the fingers 43 on the fulcrum walls 46 of the lugs 44.

What is claimed is:—

1. A closure for the mouth of a vault or other receptacle having a substantially flat abutment web within the mouth opening, comprising a door of elastic sheet metal of relatively light gage, said door being plane throughout and of a size to fit the door opening and confine flat packing material against the abutment, lock bolts movable into and out of engaging relation to the inner face of the abutment, devices on the inner face of the door close to the web and engaged by and supporting the lock bolts, and means carried by the door and engaging the latter solely at the mid-portion thereof and connected to the lock bolts for moving them into and out of locking position and 50 having means for rocking the lock bolts toward and from the inner face of the door and clamp the latter against the abutment, said means at the mid-portion of the door engaging the latter to cause it to bulge outwardly, whereby the door is elastically held against the web when the door is in the locked position.

2. A door closure for vaults and the like, having lock bolts on its inner face, and 60 means for actuating the lock bolts including an interiorly and exteriorly threaded member projecting through the door from the interior to the exterior thereof and rockable about an axis perpendicular to

the face of the door, a lock nut on the threaded member, a threaded rod extending through the threaded member from the interior to the exterior of the door and of a length to be moved axially through the threaded member for a distance, and connections between the threaded rod and the lock bolts and under the control of the threaded member for projecting and retracting the lock bolts and rocking them toward and from the inner face of the door. 75

3. A closure for vaults and the like, comprising a door of a size to close the mouth of the vault, lock bolts on the inner face of the door, an interiorly and exteriorly threaded member mounted on the door and projecting from the interior to the exterior thereof and there provided with an exterior lock nut, said threaded member being accessible at the exterior of the door for turning movements, a threaded rod extending through the threaded member from the interior to the exterior of the door and at the outer end provided with means for the application of a manipulating tool, a master plate carried by the inner end of the rod with the master plate and threaded member having coacting interlocking portions, and connections between the master plate and the lock bolts for retracting and projecting the latter by rotative movements of the master plate 80 through the interlocking portions of the master plate and threaded member. 90

4. A closure for vaults and the like, comprising a door of a size to close the mouth of the vault, lock bolts on the inner face of the door, an interiorly and exteriorly threaded member mounted on the door and projecting from the interior to the exterior thereof and there provided with an exterior lock nut, said threaded member being accessible at the exterior of the door for turning movements, a threaded rod extending through the threaded member from the interior to the exterior of the door and at the outer end provided with means for the application of a manipulating tool, a master plate carried by the inner end of the rod with the master plate and threaded member having coacting interlocking portions, and connections between the master plate and the lock bolts for retracting and projecting the latter by rotative movements of the master plate 95 through the interlocking portions of the master plate and threaded member. 100

5. A closure for vaults and the like, comprising a door of a size to close the mouth of the vault, lock bolts on the inner face of the door, an interiorly and exteriorly threaded member mounted on the door and projecting from the interior to the exterior 110 115 120 125

thereof and there provided with an exterior lock nut, said threaded member being accessible at the exterior of the door for turning movements, a threaded rod extending 5 through the threaded member from the interior to the exterior of the door and at the outer end provided with means for the application of a manipulating tool, a master plate carried by the inner end of the rod 10 with the master plate and threaded member having coacting interlocking portions, and connections between the master plate and the lock bolts for retracting and projecting the latter by rotative movements of 15 the master plate through the interlocking portions of the master plate and threaded member, the door having positioning means for the threaded member to temporarily hold it at the limits of its rotative movements, and the master plate and connections 20 with the lock bolts having coacting portions for limiting movements of the master plate in retracting and projecting the lock bolts.

6. A closure for the mouths of vaults and 25 the like, comprising a door, lock bolts on the door movable toward and from the marginal portions thereof and extending to points adjacent to a mid portion of the door, links connected to respective lock bolts, a 30 master plate connected to all the links, a rotatable screw rod carrying the master plate and projecting through a mid portion of the door to the exterior thereof for the application of a manipulating means, a 35 swiveled screw threaded member mounted on the door and projecting therethrough to the exterior thereof and traversed by the screw rod, said threaded member being accessible from the exterior of the door for 40 rocking it about its longitudinal axis, and a lock nut and packing washer on the exposed portion of the threaded member for clamping it to the door, the threaded member and master plate having coacting portions 45 for interlocking them when brought into engagement, whereby the threaded member may be turned to actuate the master plate to retract and project the locking bolts.

7. A closure for the mouths of vaults and 50 the like, comprising a door with reciprocable and rockable lock bolts having guiding means for confining the reciprocatory movements of the lock bolts to substantially straight lines, devices on the door for actuating the lock bolts in their reciprocatory movements and also for rocking the lock bolts, and links each pivoted at one end to the inner end of a lock bolt and at the other end to the actuating devices with the pivotal 55 axes at the opposite ends of each link parallel one to the other, the links constituting the sole connections between the inner ends of the lock bolts and the actuating devices and the sole means for transmitting both

the reciprocatory and the rocking movements to the lock bolts. 65

8. A closure for the mouths of vaults and the like, comprising a door, reciprocable and rockable lock bolts on the inner face of the door with the axes of rocking of the bolts 70 substantially parallel with the inner face of the door, a connecting master plate common to all the lock bolts, a rockable member carried by and projecting through the door at the middle portion thereof with the master plate and rockable member having coacting parts for causing rocking movements of the master plate by rocking movements of the rockable member and the latter having parts accessible from the exterior of the door for its manipulation, and a manipulating member threaded through the rockable member and connected to the master plate for moving the latter and the lock bolts connected to it toward and from 80 the door. 85

9. A closure for the mouths of vaults, comprising a door with reciprocatory lock bolts, guide pins on the door for the bolts, and locking means on a bolt comprising a 90 rockable plate having an elongated slot with terminal notches and extending on opposite sides of the axis of rocking of the plate, said plate also having one end movable into and out of engaging relation to a guide pin, 95 and a spring fast at one end to the lock bolt and at the other end movable in the elongated slot of the plate from one notch to the other for constraining the plate to rock in one direction or the other in accordance 100 with the position of the spring, whereby the plate may be held either in or out of engaging relation with the guide pin with which it is associated. 105

10. A closure for the mouth ends of vaults or the like comprising a door with reciprocable and rockable locking bolts on its inner face, and manipulating means for the bolts comprising a connecting member common to all of them, means for moving the connecting member toward and from the inner face of the door, and participating in such movement to rock the lock bolts, and an actuating member for the connecting member mounted and rotatable on the door and held by the door against movement toward and from the latter to move the connecting member in a direction to withdraw or project the bolts, and also carrying the means for moving the connecting member toward 110 and from the inner face of the door. 115

11. A closure for a vault or the like having an inset abutment at its mouth end, comprising a door of a size to enter the mouth of the vault and engage the abutment, and a hinge support for the door comprising a hinge member rising from the top 120 of the vault at the mouth end and provided

with facing sockets spaced apart and elongated in the direction of the length of the vault, and another hinge member fast to and rising above the top of the door, the 5 second-named hinge member having oppositely projecting pintles spaced forwardly of the plane of the door and entering and movable lengthwise of the elongated sockets, whereby the door may be 10 moved on the hinge to the open position and

to the closed position, and in the latter position may be moved bodily into the mouth of the vault toward the inset abutment.

In testimony, that I claim the foregoing as my own, I have hereto affixed my signature in the presence of two witnesses. 15
